CHARLES H. BACON, OF SPRINGFIELD, OHIO.

Letters Patent No. 72,442, dated December 24, 1867; antedated December 11, 1867.

DEVICE FOR ATTACHING POSTAGE AND REVENUE-STAMPS, &c.

The Schedule referred to in these Letters Patent and making part of the same.

TO ALL WHOM IT MAY CONCERN:

Be it known that I, CHARLES H. BACON, of Springfield, in the county of Clark, and State of Ohio, have invented a new and useful Stamp for Attaching Post-Office and Revenue-Stamps to Papers; and I do hereby declare that the following is a full, clear, and exact description of the same, reference being had to the annexed drawings, making part of this specification, in which—

Figure 1 is a perspective view,

Figure 2 is a vertical section, and

Figure 3 is a bottom view.

In the several drawings, the same letters are employed in the indication of identical parts.

A is a hollow prismatic case, the inner dimensions of which should be the exact size of the stamps intended to be used. Into this case is fitted the follower B, attached to a stem, C, passing through the top of the case. This stem is surrounded by a spiral spring, D, by which the follower is raised and held at the top of the case. The case is covered by the cover F, which also supports the sleeve F', surrounding one-half of the length of the rod C, and of internal diameter sufficient to receive the tube E, the rounded top E' of which rests upon the stem C and spiral spring D. Knives, G, are attached to the collar H, which slides over the case A, and the knives passing through inwardly-converging slots in the case A, corresponding to their own form and size, project within the inner space of the case, presenting, as seen from the side, the form of right-angled triangles having a narrow base, as shown in the section in fig. 2. I use two on the sides, near the ends, and one at the middle of the end, but the number may be increased or diminished, if necessary. I have found this number and arrangement best with ordinary postage or small revenue-stamps. Slots corresponding to the knives are cut in the edge of the follower at B'.

The case is to be filled with stamps, by taking out the follower and removing the cap F. The inclined edges of the knives G cut the stamp as pressed down by the follower, but offer sufficient resistance to hold all the stamps except the one on the outside, which adheres to the envelope or other paper. The stamp must be placed in the case with the mucilage-coated side down. A damp pad or piece of sponge is used in connection with the stamp, on which the mucilage is moistened, and then the stamp placed in position, and the top E struck or pressed with the hand. The follower B presses the stamp, which adheres to the paper, and is drawn from the case, the others immediately above it being retained by the inclined knives, as already explained.

What I claim as my invention, and desire to secure by Letters Patent, is—

The case A, having knives G, with inclined edges projecting from its interior faces, in combination with the follower B, substantially as and for the purpose set forth.

In testimony whereof, I have signed my name to this specification in the presence of two subscribing witnesses.

CHAS. H. BACON.
